UNITED STATES PATENT OFFICE.

WILLIAM G. UTSCHIG, OF SAN JOSE, CALIFORNIA.

DEVICE FOR EXTRACTING MATTER FROM INFLAMED TISSUES.

No. 901,567.

Specification of Letters Patent.

Patented Oct. 20, 1908.

Application filed April 10, 1905. Serial No. 254,867.

To all whom it may concern:

Be it known that I, WILLIAM G. UTSCHIG, citizen of the United States, residing at San Jose, in the county of Santa Clara and State of California, have invented certain new and useful Improvements in Devices for Extracting Matter from Inflamed Tissues, of which the following is a specification.

My invention relates to improvements in 10 pus and blackhead removers.

The object of my invention is to provide a device for the rapid removal of pus and blackheads from pimples, and also to take up an exact amount of medicine or any very small 15 quantity of fluid.

My device will be found especially serviceable for the removal of matter from pimples commonly known as "blackheads", obviating the necessity of exerting pressure by the 20 use of fingers or the employment of some other painful method as heretofore used by surgeons, barbers or other persons.

My invention consists in the novel combination and arrangement of parts described 25 in the following specification, shown in the accompanying drawing and claimed in the appended claims.

Referring to the accompanying drawing Figure 1 represents a side elevation of my device; Fig. 2 shows a plan view of the same, and Fig. 3 is a detail of the holder.

In the figures 1 represents a frame having an angular arm, at the end of which is a semi-circular clasp 2 having a groove 3 in which is 35 set the flange or rim 4 of a glass cylinder 5 having a nozzle 6. In the cylinder 5 is a piston 7 connected by a link and rod 8 to a lever 9, pivotally fulcrumed at 10. The groove 3 is designated by dotted lines in Figs. 1 and 2.

To operate the device the end of the nozzle described is placed upon the pimple containing pus or a black-head, then the open handles at the end of the fulcrumed arms are closed, causing the lever 9 to raise the piston 45 7 thereby creating a vacuum in the space between the base of the piston and the end of

the nozzle drawing into the cylinder by the consequent suction the pus or blackhead intended to be extracted. The opening of the handles will cause the expulsion of the object 50 drawn into the cylinder by the downward pressure of the admitted air. To raise a liquid into the cylinder the nozzle is immersed in the liquid and the operation of the handles is repeated as with the extraction of pus or a 55 blackhead. It will be seen by said drawing and description that the nozzle may be placed upon a pimple without grasping the cylinder so that pus or a blackhead may be extracted by motion with the use of but one 60 hand. Rings such as affixed to a pair of shears may be secured to the ends of the handles for the better securing of the same during their operation if desired. The cylinder 5 is preferably made of glass owing to its 65 cheapness and lightness, but metal or hard rubber may be used in its manufacture if desired.

Having thus described my invention what I claim as new and desire to secure by Letters Patent is:

In a pus and blackhead remover the combination of a cylinder having a tapering nozzle at one end and a flange at the other end; an angular arm having a handle and a vertical branch extending from said arm; a clasp 75 connected to said branch having a groove penetrated by said flange for sustaining said cylinder; a lever and handle centrally fulcrumed to said arm for the operation of said 80 remover by the closing of said handles, and a piston in said cylinder connected by a movable rod to said lever for drawing into said cylinder and expelling therefrom foreign matter to be removed by said device, substantially as described.

In testimony whereof I affix my signature in presence of two witnesses.

WILLIAM G. UTSCHIG.
